CLOSETABLE FOLDING BED

Original Filed Aug. 15, 1924

UNITED STATES PATENT OFFICE

HARRISON U. CRAIN, OF ST. LOUIS, MISSOURI

CLOSETABLE FOLDING BED

Application filed August 15, 1924, Serial No. 732,279. Renewed October 9, 1929.

This invention relates to closetable folding beds, or, in other words, those of the kind that are capable of being folded up and are hingedly mounted to swing in that condition into and out of a recess or closet through the door opening, whereby the bed may be placed out of the way and out of sight when not in use and readily placed in condition for use, at will.

10 The invention has for its objects to produce a structure which may be readily installed in connection with an already existing recess or closet without special preparation or alteration therefor; to provide for the utilization of space of minimum dimensions in width and depth in the recess or closet; to permit the use of a relatively narrow door opening; to obviate the necessity for employing any special guiding and tracking 15 means in moving the bed into and out of the recess or closet; and to attain certain advantages as will hereinafter more fully appear in the following description.

20 The invention consists in the parts and combinations and arrangements of parts hereinafter described and afterwards pointed out with particularity in the appended claim.

25 In the accompanying drawings forming part of this specification and illustrating a practical adaptation of the invention,—

Figure 1 is a horizontal section through the closet and a top plan view of the bed frame in folded up condition, the bed frame being shown in full lines in position outside of and ready to be swung into the closet or to be lowered for use, and the in and out movement of the bed frame being indicated by the several diagrams in dotted lines;

40 Figure 2 is a vertical section through the closet at the door opening, the bed frame being shown in folded up position in full lines and the lowered position of the mattress supporting portion of the frame being indicated by dotted lines; and

45 Figures 3, 4, 5, 6 and 7 are fragmentary views, on an enlarged scale, showing different positions of the swinging supporting arms and head frame to illustrate the movement 50 of the bed frame into and out of the closet.

Referring now to the drawings, the numeral 1 designates a substantially rectangular head frame or supporting carriage for the foldable mattress frame 2 of the bed. The mattress frame 2 is hinged, as at 3, to the end portions of horizontal arms 4 on the head frame 1, while at the foot end of the mattress frame folding legs 5 are provided for supporting the same in lowered position. The particular construction and arrangement of 60 the bed frame other than the particular mounting of the head frame, as will be presently pointed out, does not concern the present invention except in a general way, and, therefore, no detailed description thereof is 65 deemed necessary in this specification.

Rotatably mounted adjacent to the door jamb or pillar 6 is a vertical shaft 7. This shaft is preferably journalled and supported at its lower end in a suitable ball or other antifriction bearing 8 located either on the door sill or jamb, and at its upper end in another antifriction bearing 9 on the jamb. Pinned or otherwise fastened on the shaft 7 are two parallel arms 10, and journalled on said arms is a second shaft 11 which is preferably supported on the upper arm by a suitable antifriction bearing 12.

70 Pinned or otherwise fastened on the upper and lower end portions of the shaft 11 are 80 parallel arms 13 at the outer ends of which are upstanding trunnions on which the upper and lower horizontal members of the head frame 1 are respectively hingedly mounted, as at 14, and there provided with suitable 85 antifriction bearings, or not, as may be desired.

75 The arms 10 being fixed to the shaft 7 swing in parallel relation with each other about the axis of the shaft, and the arms 13 on the shaft 11 likewise swing about its axis. The whole structure, therefore, constitutes a toggle-jointed support for the head frame, which latter is hingedly supported on the arms 13. By this arrangement the folded up 90 bed frame may be swung readily into and out of the recess or closet through a much narrower door opening than if the head frame 1 were mounted on a single pair of arms 95 swinging about the axis of the shaft 7. 100

Preferably, a stop arrangement is provided to limit the rotative movement of the shaft 7. This may be accomplished providing the shaft with a pin 15 and cutting away a portion of a stationary part of one or both of the bearings 8, 9, to afford shoulders 16, 17, and in this case so that the shaft may be given a half turn. A similar arrangement may be provided for the shaft 11, but limiting the shaft to a quarter turn. This arrangement will ordinarily allow sufficient movement of the arms to swing the bed frame without striking the door frame or the walls of the recess or closet, and yet provide stops which facilitate the proper manipulation of the bed frame and afford limiting stops for the parts in the final positions of the bed frame both inside and outside of the closet or recess.

20. The folded up bed frame being outside the closet, as shown in full lines in Figure 1, the first movement to swing it into the closet is to swing the head frame on the pivot 14 as indicated by the arc *a b*; next swing the head frame and arms 13 to the position from that shown in Figure 7 to that shown in Figure 6, and as indicated by the arc *b c* (Figure 1); next swing the head frame, arms 13 and arms 10 to the position shown in Figure 5, and as indicated by the arc *c d* (Figure 1); next swing the parts to the position shown in Figure 4, and as indicated by the arc *d e* (Figure 1); then swing the head frame, arms 13 and arms 10 to the position shown in Figure 3—that is, with the head frame at the angle indicated by the dotted lines, and the swing being indicated by the arc *e f* (Figure 1); and, finally, swing the head frame to the position indicated by the full lines in Figure 3, and as indicated by the arc *f g* (Figure 1). In moving the bed out of the closet, the same evolutions are gone through, but in reverse order to that above described in moving it into the closet, and 45 as indicated by the arcs shown in dotted lines in Figure 1.

The herein described toggle-jointed, swinging, supporting frame, affords a foldable support for the folded up bed frame which permits the latter to be readily swung through a relatively narrow door opening. It also obviates the necessity for providing a track-way or guiding device as is necessary in some cases with other mountings for closetable beds.

Obviously, the structure admits of considerable modification without in the least departing from the spirit of the invention as defined by the appended claim. It is, therefore, not limited to the specific construction and arrangement shown in the accompanying drawings.

What is claimed is:

In a bed structure of the character described, a vertical shaft, means by which the

shaft is rotatably supported substantially centrally of the jamb of a doorway, means self-contained within the supporting means and engageable with a stop on the shaft for limiting the rotative movement of said shaft to substantially one-half turn, a plurality of parallel horizontal arms fixed on said shaft to swing in unison about the axis thereof so as to extend transversely of the jamb in their opened and closed positions respectively, a second vertical shaft, means by which the second shaft is rotatably supported on said parallel arms, means self-contained within said last mentioned supporting means and engageable with a stop on the second shaft for limiting the rotative movement of said second shaft to substantially one-quarter turn on said arms, a second plurality of parallel horizontal arms fixed on said second shaft so that, at the limit of their swinging movement, they extend at an equal angle on either side of the longitudinal axes of said first mentioned arms, and a bed frame proper hingedly mounted to swing about a vertical axis on said second mentioned arms. 90
